AUDIO FREQUENCY AMPLIFIER

Leland D. Norton, Bridgeport, Conn., assignor to
 Dictaphone Corporation, New York, N. Y., a
 corporation of New York

Application November 20, 1934, Serial No. 753,845

1 Claim. (Cl. 179—171)

This invention relates to audio-frequency amplifiers and more particularly to means for automatically controlling the gain of the amplifier whenever the audio-frequency output rises above a predetermined voltage level.

An object of the invention is to provide in an audio-frequency amplifier simple and effective means for automatically maintaining a substantially constant audio-frequency power output. 10 A further object is to provide a stable and distortionless means for effecting wide variation of the amplification factor at one or more stages of a multi-stage audio-amplifier in response to slight changes above a predetermined power level. 15

Thermionic amplifiers have heretofore been used in transmission systems receiving voice frequency currents from telephone lines or directly from microphones, in order to provide sufficient energy for recording the voice frequencies upon phonograph records. In order that such record be relatively free from distortion and to prevent blasting when the voice currents rise above a desired amplitude, it has been found necessary to control the power gain of the amplifier so as to compensate for variations in the power level of the input circuit feeding to the amplifier. If automatic control means are to be employed, it becomes essential to insure that the rate of variation of the amplification factor of the thermionic devices be kept well below the lowest audio-frequencies within the range of the recording mechanisms. It is accordingly a further object of this invention to provide an automatic volume control having a time constant relatively large as compared with the lowest audio-frequency to be recorded.

Other objects of my invention will be pointed out in the following description taken in conjunction with the drawing, the single figure of which illustrates one embodiment of my invention as applied to an audio-frequency amplifier of special design connected inductively to an input circuit and also connected inductively to an output circuit, the latter including suitable phonographic recording devices.

The invention accordingly consists in the features of construction, combinations of elements, and arrangements of parts as will be exemplified in the system to be hereinafter described and the scope of the application of which will be indicated in the following claim.

Referring to the drawing, the amplifier, indicated generally by A will be seen to be of the three-stage type with a transformer input to the first stage, which comprises a variable mu electron tube V—1 of the type 58. The second stage includes a tube V—2 of the same type which is resistance coupled to the output of the

first stage. The third and final stage of the amplifier, which is transformer coupled to the second stage, comprises two electron power tubes V—3—V—4 of the type 45 arranged in push-pull relation. The output of the push-pull stage is 5

transformer coupled to an output circuit containing phonographic recording devices. A control tube V—5 of the type 56 is coupled to the output circuit in shunt with the recording devices and to the grid circuits of the tubes V—1—10 V—2.

The power supply for the amplifier comprises a power transformer T, a full wave rectifier E, a filter F and a voltage divider R.

A signal input circuit I includes the primary coil 4 of an audio-frequency transformer 5. The input circuit I may be suitably connected to a telephone transmission line by 0.1 mfd. blocking condensers C—1 and C—2, to a microphone circuit, or to any other circuit suitable for impression of signal voltages at voice frequencies upon the transformer primary 4.

Tube V—1 comprises a plate 7, a cathode 8, a filament 9 for heating the cathode 8, a control grid 10, a screen grid 11, and a suppressor grid 12. In the present arrangement, as it has been found desirable to decrease the amplification factor of tube V—1, the suppressor grid 12 of that tube is connected to the plate 7. The input circuit of the tube V—1 includes the secondary coil 13 of the transformer 5 which is connected 25 to the control grid 10 by the conductor 14. A grid resistor R—7 of about 250,000 ohms is connected across the coil 13. Coil 13 is also connected by means of a resistor R—1 (0.1 meg.) and connection 16 at a point 17 with a line 18, 30 connected by means of a slider contact 19 with a resistance element R—15 (500 ohms) of the voltage divider R. The cathode 8 of the tube 35 V—1 is connected at 21 to a conductor 22, connected at 23 to the voltage divider R, which at 40 that point is grounded as indicated at 24. The positive end of the voltage divider is indicated at 25 and the negative end at 26. The control grid 10 is normally negatively biased with respect to the cathode 8 by the voltage drop across 45 the portion of the resistance element R—15 extending to the right of the slider 19.

The filament of tube V—1 as well as those of tubes V—2 and V—5 are connected, as indicated by the conductors X—X, to a secondary 50 coil 43 of the power transformer T, the primary 28 of which receives energy from a 110-120 volt, 60-cycle alternating source. A full-wave rectifier tube E has its anode plates 30, 31 connected respectively to the extremities of the 55 secondary coil 32 of transformer T. The cathode 33 of rectifier tube E is heated by current supplied by secondary coil 34 of the transformer. The midpoint 35 of coil 32 is connected to the negative side of the voltage divider R by a suit- 60

able conductor 36. The positive side of the voltage divider is connected by means of a line 37 to the midpoint of the secondary coil 34 through the choke coils 38 and 39. These coils in conjunction with the filter condensers 40, 41 and 42 serve to smooth out pulsations in the unidirectional pulsating current supplied to the terminals of the voltage divider by the rectifier E. A further secondary coil 45 supplies current to the filaments of the tubes V-3-V-4 as indicated by the conductors Y-Y.

Returning to the description of the amplifier, the plate 7 of tube V-1 is connected through the coupling resistor R-3 (0.1 meg.) to a conductor 47 connected at 25 to the positive end of the voltage divider R. The plate circuit return is made through the cathode 8 to the point 23 of the voltage divider. Thus the plate circuit of tube V-1 includes resistance element R-16 (20,000 ohms) of the voltage divider. The screen grid 11 of the tube V-1 is connected by means of a conductor 49 and resistor R-4 (25,000 ohms) to a slider 50 which has movable contact with the element R-16 of the voltage divider. Thus the potential of the screen grid may be varied as desired. The screen grid to cathode circuit is shunted by a condenser C-4 (0.5 mfd.) and a resistor R-2 (0.1 meg.) which serve as a filter for that circuit. A similar filter comprises a condenser C-9 (2. mfd.) shunted across the control grid to cathode circuit of tube V-1 and the resistor R-1.

The plate 7 of tube V-1 is connected to the control grid 54 of the tube V-2 through a blocking condenser C-12 (0.006 mfd.). The plate 51 of tube V-2 is connected through the primary coil 58 of an audio-frequency transformer 59 through a suitable resistor R-9 (75,000 ohms) to the conductor 47. The cathode 61 of tube V-2 is connected as at 62 to conductor 22. The plate to cathode circuit of tube V-2 is, therefore, connected across the same resistance element of the voltage divider as the similar circuit of tube V-1. As with tube V-1 the suppressor grid 63 is connected to the plate 57. Since the second amplifier stage is transformer coupled to the push-pull stage the tube V-2 need not have as high an amplification factor as tube V-1. It is desirable, however, that it have greater distortionless power capacity. Hence the screen grid 64 is connected directly to the suppressor grid 63 and plate 57. The control grid circuit of tube V-2 includes the resistors R-5 (250,000 ohms) and R-6 (.1 meg.) and is connected through the conductors 16 and 18 to the slider contact 19 and the voltage divider. Thus the control grid bias for tube V-2 is provided by the voltage drop across the same portion of resistance element R-15 that provides grid bias for tube V-1. A condenser C-7 (0.5 mfd.) provides an audio-frequency path between transformer primary and cathode 61. A condenser C-5 (0.5 mfd.) provides a by-pass between cathode 61 and grid resistor R-5.

The amplified audio-frequency voltages on the plate 57 are impressed upon the grids 70 and 71 of tubes V-3 and V-4, the impressed voltage being derived from the secondary coil 74 of transformer 59. The return circuit for the two grids 70 and 71 is by means of a wire 75 connected to the midpoint of transformer coil 74 and leading to the negative side 26 of voltage divider R. The filament cathodes 76 and 77 of these tubes are connected through the lines

Y-Y directly to the terminals of the secondary coil 45 of power transformer T. The midpoint of this coil is connected through a biasing resistor R-17 (1,000 ohms) to the negative side of the rectifier to voltage divider circuit at a point 79. Thus the amount of negative bias at the grids of the push-pull amplifier tubes is determined by the resistor R-17. The plates 80 and 81 of amplifier tubes V-3 and V-4 are connected together through the primary coil 82 of the output audio-frequency transformer 83. The midpoint of this coil is connected through a resistor R-18 (1,000 ohms) to a point 85 in the positive side of the power rectifier circuit between the choke coils 38 and 39. The resistor R-18 is selected to provide a sufficiently high voltage in the plate to cathode circuit of the push-pull tubes and since the plate to cathode circuits of this stage of the amplifier do not include resistances of the voltage divider there is small chance for feed-back from the output stage to the earlier stages of the amplifier. The secondary coil 86 of transformer 83 is connected by means of an output circuit, including a condenser C-8 (0.5 mfd.) in its high potential side, to one or more phonographic recording instruments as indicated at 87 and 88. The low potential side of this output circuit is grounded as at 85.

When the input circuit 1 receives voice currents from a microphone, telephone circuit, or otherwise, each amplifier stage will increase the energy of such voice currents and if the amplifier is properly designed sufficient energy will be delivered to the recording instruments 87, 88 to enable them to cut sound grooves upon the records used in connection therewith. Unfortunately, the power level of the input circuit 1 may vary, for example, from +10 to -40 db., rating 0 at 0.006 watt. Therefore, it is not possible always to get satisfactory recording results with an amplifier of this type unless compensation is made for such variations in input power level. Such variations are particularly likely to occur where the amplifier is connected alternately to long and short telephone transmission lines. Now suppose the input circuit power level to be -40 db. and that there is an input circuit coupling loss of 20 db. Then, if for satisfactory recording results it is desirable to hold the power level in the output circuit at +20 db., it follows that the amplifier must have a maximum power gain of at least 80 db.

But should the energy level of the input circuit rise to -20 db. it would follow that the 80 db. gain of the amplifier would result in a too high power level in the output circuit.

From such a condition there would arise a lack of uniformity in the amplitude of the recording, causing the records to vary greatly in loudness when reproduced; and even in respect to a single record, great differences in loudness would occur at different points in the record.

To obviate this difficulty the present amplifier has been provided with an automatic volume control comprising an electron tube V-5 of the type 56. The cathode 90 of this tube is connected at point 91 to the voltage divider. The control grid 92 is connected by means of a slider contact 93 with the resistance element R-12 (2,000 ohms) of the voltage divider through the grid resistor R-10 (0.1 meg.). The grid 92 is also connected by a wire 96 through a condenser C-3 (0.1 mfd.) at a point 98 with the high potential side of the output or load circuit. The

plate 99 of tube V-5 is connected to the conductor 18 and thus to slider contact 19 and the voltage divider. A resistor R-11 (0.1 meg.) is included in the conductor 18 at a point between its connection with the plate 99 and the slider 19. The plate circuit of the tube V-5 thus includes resistor R-11, resistance element R-13 (7,000 ohms) and the lefthand portion of R-15, while the grid to cathode circuit of the said tube includes that portion of the voltage divider resistance R-12 that is disposed between the slider contact 93 and the point 91. It will be seen that the resistor R-11 is included not only in the plate circuit of the control tube V-5 but also in the grid circuits of the variable mu amplifier tubes V-1 and V-2. This resistance provides the means for varying the grid bias of the variable mu tubes in response to variations in the energy level of the output circuit impressed on the grid 20 of V-5.

Normally, in operation, the slider contact 93 is adjusted so as to provide a negative potential on the grid 92 of the control tube of such value that the control tube is biased approximately to cut-off. The biasing of grid 92 by means of the 25 slider contact 93 is adjusted so that until the energy of the output circuit exceeds a predetermined level a negligible quantity of current will flow in the plate circuit of the control tube V-5. When, however, the said output energy rises even slightly above its predetermined level the grid 92 of the control tube will become more positive and current will flow through the plate circuit thereof and through the resistance R-11. 30 The voltage drop across the resistance R-11 will cause the control grids 10 and 54 of the variable mu tubes V-1 and V-2 to become more negative and thus reduce the amplification factors of these tubes. By proper designing, the control tube may be made to produce great variation in the amplification factors of the variable mu tubes in response to very slight increases in the power level of the output circuit. As soon as the 35 decreased amplification of the tubes V-1 and V-2 effects sufficient reduction in the output level, current of any appreciable value will cease to flow through the resistor R-11 and the grids of the tubes V-1 and V-2, becoming again more positive, the amplification factors of those tubes 40 will increase in value. In this way a substantially constant power level may be maintained at the output stage of the amplifier irrespective of the intensity of the voice currents received at the input stage thereof.

It should here be noted that the automatic 55 control of the amplification factors of variable mu tubes in a plurality of different stages of the amplifier presents a problem quite different from that where control is confined to a single stage. The maximum amount of amplification allowed to the tubes of each stage becomes an important 60 factor. Since as in the present embodiment of the invention the grids of the two controlled tubes are connected to the same control element 65 and receive their normal voltage bias from the same source, it is highly important that proper means be employed to prevent feed-back between the respective grid circuits. This purpose is attained herein by shunting a condenser C-10 (1. 70 mfd.) across the grid cathode circuits of the controlled tubes. This condenser serves also to

determine the time constant of the control circuit which is substantially equal to the product of the series resistance R-11 and the shunt capacitance C-10. By properly determining the value of capacitance C-10 in relation to resistance R-11 any desired time constant may be attained. Practically this is adjusted so that there will be sufficient delay to prevent a rapid shift from low to high amplification and vice versa between syllables or words of the matter 10 recorded.

To obtain the best results tubes V-1 and V-2 are operated at ground potential. The grounding of their cathodes at 24 tends to stabilize the circuits of these tubes. The grid circuit of the 15 control tube is also grounded through a condenser C-13 (4 mfd.).

Another important feature of the present amplifier is the resistor R-1, which tends to stabilize the grid circuit of the first amplifier tube 20 V-1.

It will be seen that there is provided a construction of an essentially practical nature in which the several objects of this invention are attained.

As many possible embodiments may be made of the above invention without departing from the scope thereof, it is to be understood that all matter herein set forth or shown in the accompanying drawing is to be interpreted as illustrative and not in a limiting sense.

I claim:

In an audio-frequency amplifying system of the type wherein the vacuum tube amplifier derives its operating potentials from a potentiometer connected across a direct current source of power, a vacuum tube control circuit deriving its necessary operating potentials from said potentiometer and adapted to cause a grid bias of 35 said amplifier to become more negative as the output of said amplifier increases, comprising, in combination, a control vacuum tube having a cathode, anode and grid, a capacitative connection from said grid to said amplifier at a point which varies in potential in accordance with the 40 audio-frequency output of said amplifier, another connection from said grid through a first resistance to an adjustable tap on said potentiometer at a first point near the negative end thereof, said first point being effectively grounded through a first condenser, a connection from said potentiometer at a second point intermediate its ends to ground and to a cathode of 45 said amplifier, a connection from said control tube cathode to said potentiometer at a third point intermediate said first and second points, a connection from said control tube anode to a 50 grid circuit of said amplifier and through a second resistance to an adjustable tap at a fourth point on said potentiometer intermediate said 55 second and third points, a second condenser connected between said anode and said second point, the values of said second resistance and said second condenser determining the time constant of 60 operation of said control circuit, and other necessary operating circuits of said amplifier deriving their potentials from said potentiometer at 65 points between the positive end thereof and said second point.

LELAND D. NORTON. 70
